UNITED STATES PATENT OFFICE.

LEO H. WISE, OF NEW YORK, N. Y., ASSIGNOR TO WISE BROTHERS, OF BALTIMORE, MARYLAND, A FIRM COMPOSED OF EDWARD H. WISE, LEO H. WISE, AND HENRY E. WISE.

OVERALLS.

1,145,855.

Specification of Letters Patent.

Patented July 6, 1915.

Application filed January 28, 1915. Serial No. 4,812.

To all whom it may concern:

Be it known that I, LEO H. WISE, a citizen of the United States, residing at New York, in the State of New York, have invented certain new and useful Improvements in Overalls, of which the following is a specification.

This invention relates to improvements in overalls and has for its object to provide an improved construction of garment of this character, comprising trousers and jacket portions, whereby the trousers portion may be worn with or without the jacket and when worn with the jacket an undue amount of material above the waist line and at the front will be avoided.

Another object of the invention is to provide a two piece overall comprising trousers and jacket portions,—the trousers portion having a bib at the front which extends upwardly from the waist band and the jacket portion having a cut-out at the front into which the bib projects and to provide fastenings to secure the bib to the jacket.

A further object is to provide a two piece overall,—the trousers portion of which has a bib and the jacket portion a cut-out to receive the bib and to provide fastenings along the lapped edges of the cut-out and bib.

With these and other objects in view, the invention is illustrated in the accompanying drawing, wherein,—

Figure 1, shows a front view of the two piece garment,—the trousers and jacket portion being connected at bib and cut-out portions. Fig. 2 illustrates the detached jacket in front elevation. Fig. 3, shows the upper bib-portion of the trousers also in front elevation, and Fig. 4 shows a rear view of the trousers and a rear view of a portion of the jacket and further illustrates the shoulder straps for holding the rear of the trousers up.

Referring to the drawing by numerals 5, 45 designates the jacket front, and 6, the back thereof. The front of the jacket has a central vertical lapped portion 7, which extends downwardly a short distance only from the collar 8, so the two sides of said front may be secured in a central lapped condition by suitable fastenings 9. The lower edge 10, of this central vertical lapped portion terminates well above the lower edge 11, of the back 6, and from said edge 10, the front has 50 downwardly extending and outwardly di-

verging edges 12, which form a front cut-out. Both of these diverging front edges 12, are preferably provided with fastening members, which, in the present instance, have the form of buttonholes 13. Sleeves 14, 60 are provided in the jacket to complete that garment portion.

The trousers 15, have the usual legs 16, and front fly 17, and are also provided with vertical slits 18, at opposite sides which 65 slits may be closed by means of buttons 19, or equivalent fastenings attached to the two edges of the slits. A reinforcing band 20, preferably extends across the front from one slit to the other. A bib 21, extends upwardly at the front of the trousers portion from the band 20, and said bib has a shape substantially corresponding to the shape of the cut-out in the front of the jacket. In the present instance, the opposite edges 22, of 70 the bib extend upwardly in an inclined direction from the band 20, and, if extended far enough would converge, and each of said inclined edges of this bib is provided with fastening members, such as buttons 23, 75 which may be engaged with the coacting fastenings or buttonholes 13, in the diverging front edges 12, of the jacket.

From the foregoing explanation it will be understood that the bib portion 21, at the 85 upper front edge of the trousers fits into and preferably underlaps, the edges of the cut-out at the front of the jacket, and said edges are joined or fastened by means of the fastening members 13 and 23, so that the bib is 90 secured to the jacket along the inclined lapped edges. The rear edge 24, of the trousers has position above the lower rear edge 11, of the jacket so that the jacket edge 95 at the rear will depend below the trousers edge. At the rear, the jacket edge 11, is free so as to give a freedom of movement of the body that would otherwise be restricted. Suitable suspender straps 25, have rear ends 100 detachably connected to the rear edge of the trousers, and may be passed over the shoulders so that their front ends can be attached to fastenings 26, on the upper edge of the front bib.

By means of the construction described, 105 the two pieces of the garment may be worn together, or the jacket may be left off, but when the jacket is worn with the trousers, the bib will be held in place and prevented from bulging when leaning over or stooping, 110

and a double thickness of jacket and bib at the front will be avoided.

Having thus described my invention what I claim is,—

- 5 1. A two piece overall garment comprising jacket and trousers,—the jacket having a cut-out at the front and the trousers having a bib portion that extends up into the jacket cut-out, and means for holding the
- 10 10 bib up into said front cut-out of the jacket.
- 15 2. A two piece overall garment comprising jacket and trousers,—the jacket having a cut-out at the front and the trousers having a bib portion that extends up into the jacket cut-out and means on the edges of the cut-out and the bib to secure the bib to the jacket.

3. A two piece overall garment comprising jacket and trousers,—the jacket having a central vertical lapped front portion extending downwardly from the upper edge and terminating well above the rear of the jacket and from the lower edge of the lapped portion said front of the jacket having a cut-out with diverging and downwardly-extending edges, the trousers having a front bib that extends up into the jacket cut-out and means for securing the bib to the jacket.

In testimony whereof I affix my signature in presence of two witnesses.

LEO H. WISE.
